UNITED STATES PATENT OFFICE.

ARTHUR F. BROWN, OF DAYTON, OHIO, ASSIGNOR TO THE STODDARD MANUFACTURING COMPANY, OF SAME PLACE.

COMBINED SEEDER AND HARROW.

SPECIFICATION forming part of Letters Patent No. 408,290, dated August 6, 1889.

Application filed November 2, 1888. Serial No. 289,794. (No model.)

To all whom it may concern:

Be it known that I, ARTHUR F. BROWN, a citizen of the United States, residing at Dayton, in the county of Montgomery and State 5 of Ohio, have invented certain new and useful Improvements in Combined Harrows and Seeders, of which the following is a full, clear, and exact description, reference being had to the accompanying drawings, forming 10 part of this specification.

My invention relates to a harrow of that class known as "rotary disk harrows," upon which is mounted a seed-box whose feeding mechanism is operated from one or both of 15 the disk-gangs; and it has for its object the improvement in the construction and mode of operation of such machines.

The novelty of my invention will be herein set forth, and specifically pointed out in the 20 claims.

In the accompanying drawings, Figure 1, Sheet 1, is a plan view of a harrow embodying my invention, but with the seed-box removed. Fig. 2, Sheet 2, is a side elevation of the machine. Fig. 3, Sheet 2, is a rear elevation of the machine. Figs. 4, 5, 6, and 7, Sheet 3, are 25 enlarged details, to be referred to more particularly hereinafter. Figs. 8, 9, and 10, Sheet 4, are likewise enlarged details, to be referred 30 to more particularly hereinafter.

The same letters are used to indicate identical parts in all the figures.

The frame of the machine is composed of the following parts: The tubular metal cross-bar A, to each end of which is secured a downwardly-curved and tapering casting B, whose upper end, embracing the bar A, is slotted on each side, as at a, Fig. 4, and provided with ears b to receive clamping-bolts 35 c, and whose lower end is provided with a vertical spindle d, the central forwardly-projecting metal L-bars C, Figs. 1, 8, and 9, bolted to the bar A at their rearends and connected at their forward ends by the cross-bar D, 40 Figs. 2, 8, and 9, riveted to the bars C, the driver's seat-beam E, secured to a cross-bar F, attached to the bars C, and the brace-rods G, Figs. 1 and 2, extending from an arch-bar H upon the bars C back and outwardly to

eyes or lugs e upon the castings B, the whole 50 forming a strong, light, and rigid frame-work.

The revolving disk-gangs I, arranged to throw the earth outwardly, are of the usual or any suitable construction and have the thimbles J, between the second and third outer disks, enlarged and provided with rearwardly-projecting vertically-perforated lugs f, in which the spindles d are inserted and secured with keys g, thus forming hinges on which the gangs can be angled as desired, 60 and with sufficient play in the joint to permit the gangs to vibrate vertically and independently for a limited distance, to follow the inequalities of the ground.

In Fig. 1 I have shown a three-horse hitch 65 with a well-known form of draft-equalizer, of which the doubletree K is pivoted to a slide L, confined between the bars C, and whose slotted sides embrace the horizontal portions of said bars. To a strap M, Figs. 8 and 9, 70 connecting the slide L to the under side of the doubletree-bolt, is secured a pendent casting N, having two vertical perforations h, through which are inserted the forward perforated ends of two draw-bars O, one for each 75 of the disk-gangs, and each of which extends back and has its rear end bent downward, (see Figs. 1 and 6,) and has its spindle-shaped end inserted through a perforation in a lug i upon the forward side of the thimble P between the two inner disks of each gang, and has its elbow united by a hook j to a strap-bar k, secured to and extending up from said thimble, thereby forming a secure and what I designate a "compensating" 85 hinge-joint.

Pins l are inserted through the perforations in the forward ends of the draw-bars and bear against the forward side of the casting N.

To hold the slide L locked from forward 90 movement and to adjust it backward or forward to determine the position of angling of gangs by the power of the team and the resistance of the earth, I employ the lock-lever Q, pivoted, as at m, and provided with a pivoted dog n, engaging with a segment-rack o upon the bars C, and united to the slide L by the pivoted link R. The lever Q may have 95

an upper removable extension S, with the usual latch mechanism for lifting the dog n; or the dog n may have a rear extension T, Figs. 2, 3, and 8, by which the dog and slide 5 can be operated from the rear of the seed-box, as will be readily understood. To prevent the gangs from rising too far at their inner ends, I provide stops U, Figs. 1 and 8, which project down from the bars C over the 10 upper edges of draw-bars O.

The scrapers V for each gang are pivoted to arms p, strung and adjustably held by means of set-screws q upon a bar W, preferably square in cross-section, and adjustably held in a perforated head projecting from and secured to the bar K, and another head s upon a bar t, secured to and extending up from the lug f. Thus it will be seen that the scrapers 15 can be individually adjusted to or from the disks and can also be adjusted in a body by sliding the bars W.

The seed box or hopper y, of the usual or any suitable construction, is supported upon and removably connected to the frame by 20 means of the two rear strap-bars u, which extend down from the rear side of the hopper and are secured by screws or bolts to lugs v upon the castings B, and by the two convergent strap-bars w, which extend forward 25 from the hopper and are screwed or bolted to the bars C.

Upon the convex side of the inner disk of one of the gangs is a sprocket-wheel A', Figs. 1, 3, 6, and 7, from which a chain B' extends 30 up to a sprocket-wheel C', having a clutch-hub a', and loose upon a spindle D', journaled in a box or sleeve E', secured to an upper extension of the bar k. Feathered upon the spindle D', by side of the hub a', is a second 35 clutch-hub b', Fig. 10, having an annular recess c' and a slot for the feather or pin d', secured to the spindle. A spring e', surrounding the spindle between a collar or nut f' upon its end and the clutch b', normally holds 40 the latter in engagement with the clutch a', so that the revolution of the sprocket C' is transferred to the spindle D', as will be readily understood. To stop the revolution of the 45 spindle at any time, it is only necessary to draw back the clutch b' until it is disengaged 50 from the clutch a' and the pin d' is out of its slot, whereupon by turning the clutch b' slightly the pin d' is caught against the wall of the recess c' and the clutch locked out of 55 engagement.

The revolution of the spindle D' is communicated to the feed-shaft F' of the hopper by means of a rod G', Figs. 2, 3, and 7, united by gimbals H' to the spindle D' at its lower end 60 and to a short spindle I', journaled in boxes secured to the rear side of the hopper and carrying a pinion g', meshing with a pinion h' upon the shaft F'. The rod G', preferably square in section, is free to slide in its socket 65 in one of the gimbal-sections to enable it to accommodate itself to the movements of the gang.

The seed cups and spouts of the hopper are of the usual or any suitable construction, and while I have shown the machine with thills secured to a cross-bar T' upon the bar D, it is evident that a pole may be employed as well where a two or a four horse hitch is desired. 70

Having thus fully described my invention, I 75 claim—

1. The cross-bar A, composed of tubular metal and having secured upon its ends the curved tubular castings B, provided with the slots a and clamping-bolts c, in combination 80 with the main frame and the disk-gangs hinged to the vertical spindles of the castings B, substantially as and for the purpose specified.

2. The main frame composed of the tubular cross-bar A, having secured upon its ends the curved tubular castings B, the L-bars C, bolted to the cross-bar A and united at their forward ends by the bar D, and the brace-rods G, extending from the forward ends of 85 the bars C to the castings B, in combination with the disk-gangs hinged to the castings B, substantially in the manner and for the purpose specified. 90

3. The combination, with the sliding double-tree and its slide L, of the casting N, having vertical slots h, the draw-bars O, having their forward ends inserted through and confined in said slots and their rear ends bent down and hinged to the inner ends of the disk-gangs, the hooks j, uniting the elbows of the draw-bars to upward extensions from the gang-axes, the main frame, and the disk-gangs hinged thereto, substantially as described. 95

4. The combination, with the seed-box, its feed-shaft, and distributing mechanism, of the main frame, the disk-gangs hinged thereto, a sprocket-wheel upon the convex side of the inner disk of one gang, a second sprocket-wheel carried by said gang, a drive-chain 100 uniting the sprockets, a spindle driven by said sprockets and carried by said gang, and a drive-rod with universal joints uniting said spindle and the feed-shaft, substantially as 105 and for the purpose specified. 110

5. The combination, with the seed-box, its feed-shaft, and distributing mechanism, of the main frame, the disk-gangs hinged thereto, a sprocket-wheel upon the convex side of the inner disk of one gang, a second sprocket-wheel carried by said gang, a drive-chain 115 uniting the sprockets, a spindle driven by said sprockets and carried by said gang, clutch mechanism uniting said spindle and second sprocket, and a drive-rod with universal joints uniting said spindle and the feed-shaft, substantially as and for the purpose specified. 120

6. The combination of the doubletree K, slide L, bars C, lever Q, link R, uniting the lever to the slide-rack o, dog n, pivoted to the lever and engaging with the rack, the rear extension T from said dog, and the draw-bars O, connected at their forward ends to the 125 130

doubletree and at their rear ends to the inner ends of the disk-gangs, substantially as and for the purpose specified.

7. The combination, with the hinged disk-gang shafts, of arms projecting upwardly therefrom and movable therewith and carrying scraper-bars adjustable in said arms and

provided with independently - adjustable scrapers, substantially as and for the purpose specified.

ARTHUR F. BROWN.
